Atty.

UNITED STATES PATENT OFFICE.

AARON M. PAREIRA, OF MARINETTE, WISCONSIN.

WATER-COOLING SYSTEM FOR INTERNAL-COMBUSTION ENGINES.

1,373,445.

Specification of Letters Patent.

Patented Apr. 5, 1921.

Application filed April 12, 1920. Serial No. 373,283.

To all whom it may concern:

Be it known that I, AARON M. PAREIRA, a citizen of the United States, residing at Marinette, county of Marinette, State of Wisconsin, have invented a certain new and useful Improvement in Water-Cooling Systems for Internal-Combustion Engines, of which the following is a specification, reference being had to the accompanying drawing, forming a part thereof.

This invention relates generally to automobiles and more particularly to a certain new and useful improvement in water-cooling systems for the internal combustion engines of automobiles and the like.

It is a well known fact that engine-freezing in cold weather is one of the great sources of trouble and expense to automobileists. It is the common practice today to use alcohol and so-called non-freezing compounds in the automobile-radiator, as well as engine-hood covers, to prevent engine-freezing; such means, however, have, so far as I am aware, been found most inadequate in positively preventing engine-freezing. It is the chief object of my present invention to provide, in connection with the water-cooling system of the engine, an apparatus which will substantially entirely do away with, and consequently obviate the expense and inconvenience resulting from, engine-freezing.

With the above and other objects in view, my present invention resides in the novel features of form, construction, arrangement, and combination of parts hereinafter described and afterward pointed out in the claims.

In the accompanying drawing—

Figures 1 and 2 show in diagram an automobile internal combustion engine and its water-cooling system equipped with an apparatus embodying my invention; and

Figs. 3 and 4 show in enlarged section the several positions of the preferred form of valve employed in, and forming part of, the apparatus for directing the flow of water or other fluid to and from the water-jacket of the engine.

Referring now more in detail to the said drawing, in which like reference characters refer to like parts throughout the several views, I have shown my new apparatus in connection with an automobile internal combustion engine of standard construction, of which 1 indicates the water-jacket of the

engine, 2 the water-radiator constituting the normal water-supply tank for the jacket 1, 3 the outlet or discharge pipe from the radiator or tank 2 to the jacket 1, and 4 the return-pipe from the jacket 1 to the radiator or tank 2. Having communicating connection with the pipe 3, as shown, is the circulating pump 5 driven, as is common, by means such as the pulley 6, which is belt or otherwise suitably connected with the engine-shaft, not shown.

7 indicates what I may designate as a four-way valve for directing or controlling the flow of water to and from the jacket 1. 70 This valve 7 is located preferably as seen in Figs. 1 and 2 and is adapted for communication through a pipe-connection 8 with the jacket 1, through a pipe-connection 9 with the outlet side of the pump 5, 75 through a pipe-connection 10 with a pipe 11 leading to, and communicating with, a storage-supply-tank 12, and through a pipe-connection 13 with a pipe 14 leading back to, and communicating through pipe 3 or otherwise with, the inlet or suction side of the pump 5.

Having connection with the stem 15 of valve 7, is an arm 16, which, in turn, is pivoted to an operating lever or rod 17, which 85 extends rearwardly, as shown, to adjacent the instrument-board of the automobile for convenient manipulation by the automobile-driver.

The storage-tank 12 is suitably mounted 90 upon the automobile, preferably under the cowl, as shown, at about the top level of the radiator or tank 2 to prevent overflowing. This storage receptacle or tank 12 is preferably substantially similar in construction 95 to what are commonly known as thermos tanks, being surrounded by and inclosed within an insulating shell or covering 18, so that the water therein will be subjected to a minimum of heat radiation or effusion 100 and thereby maintained for a more or less extended period of time at its entering temperature.

Leading from the tank 12 and communicating with the pipe 3, is a return pipe 19, 105 interposed in which are valves 20 and 21, the former for controlling the flow of water from the tank 12 back to the tank 2 or to the pump 5, forming part of the normal cooling system of the engine, and the latter 110 being adapted as a drain for the complete system, including, if desired, the tank 12.

In use or operation, we will first assume that the radiator or normal supply tank 2 has been suitably filled with water and valve 7 to be in normal position or in the position 5 thereof illustrated in Fig. 3, the pump 5 being merely in communication through valve 7 with the jacket 1. Valves 20 and 21 are, of course, in closed position. The cooling system of the engine will now operate as 10 is usual, the water from tank 2 being pumped through pipe 3 and pump 5 into the jacket 1 and returning through pipe 4 to the radiator for cooling. However, should the automobile be stopped in cold, 15 freezing weather, and it be desired to obviate engine-freezing, valve 7 is manipulated by means of its operating rod 17 to the position thereof illustrated in Fig. 4, communication being thereby established 20 through the valve 7 and its said pipe-connections between the outlet-side of the pump 5 and the tank 12 and between the jacket 1 and the suction or inlet-side of the pump, communication being broken, as will be 25 noted, between the jacket 1 and the discharge or outlet-side of the pump 5. The engine continuing to temporarily run, the pump 5 will now operate to pump the water 30 from normal supply tank or radiator 2 into the tank 12; at the same time, water in the jacket 1 will be drawn back to the suction or inlet-side of the pump 5 and then also pumped into the tank 12, the cooling system 35 of the engine being thus substantially entirely drained into the storage-tank 12, where, as before mentioned, the water will be maintained at its entering temperature for a considerable period of time, and this water being more or less hot, due to the running 40 of the engine, freezing is thus, not only in the system, but also in the tank 12, positively obviated.

On again starting the automobile, valve 7 is reversely actuated to normal position 45 or to the position thereof illustrated in Fig. 3, breaking communication between the jacket 1 and the suction side of the pump 5 and opening or establishing the normal communication between the jacket 1 and the 50 outlet or discharge side of the pump 5, and also breaking communication between the tank 12 and the outlet or discharge side of the pump. Valve 20 being now opened, water from tank 12 flows into the normal 55 supply tank 2, and the engine then operating, the cooling system of the engine will function normally, valve 20 being again and in due course actuated to closed position to interrupt the flow of water from tank 12 60 to the normal system.

Thus, by comparatively simple means, I eliminate substantially any danger of engine freezing. The apparatus is positive in its operations, may be readily and inexpensively installed in connection with the en-

gine and its cooling system, may be conveniently and easily operated substantially at will, and but little time is consumed in either draining the system into the tank 12 or in again supplying the system from the tank 12. It will be evident that tank 12 may be also employed as an auxiliary supply tank for the system, providing a convenient storage receptacle for an extra supply of water for the system, and that valve 21 provides 75 convenient means for a normal draining of the entire system. As seen in Figs. 1 and 2, pipe 11 is also preferably provided with a suitable valve 22, which, with the valve 20 may be employed, when desired, to close off 80 communication entirely between the tank 12 and the normal cooling system of the engine.

I am aware that changes in the form, construction, arrangement, and combination of 85 the several parts of my new apparatus may be made and substituted for those herein shown and described without departing from the nature and principle of my invention.

Having thus described my invention, what I claim and desire to secure by Letters Patent is:

1. An internal combustion engine and its water-jacket, in combination with a water-supply tank for the jacket, a water-storage tank, and communicating connections including a pump between the jacket and tanks, the pump being operable for supplying the jacket from the supply-tank and for 95 draining both the supply-tank and jacket into the storage-tank.

2. An internal combustion engine and its water-jacket, in combination with a water-supply tank for the jacket, a water-storage tank, communicating connections including 105 a pump between the jacket and tanks, and a valve interposed in said connections for directing the flow of fluid therethrough, the pump being operable for supplying the 110 jacket from the supply tank and for draining both the supply-tank and jacket into the storage-tank.

3. An internal combustion engine and its water-jacket, in combination with a water-supply tank for the jacket, a water-storage tank, communicating connections including 115 a pump between the jacket and tanks, a valve interposed in said connections for directing the flow of fluid therethrough, and means 120 for actuating the valve at will, the pump being operable for supplying the jacket from the supply-tank and for draining both the jacket and the supply-tank into the storage-tank.

4. An internal combustion engine and its water-jacket, in combination with a water-supply tank for the jacket, a water-storage tank, communicating connections including 125 a pump between the jacket and tanks, a 130

- valve interposed in said connections for directing the flow of fluid therethrough, means for actuating the valve at will, the pump being operable for supplying the jacket from the supply-tank and for draining both the jacket and supply-tank into the storage-tank, and additional communicating connections between the storage-tank and the supply-tank for re-supplying the supply-tank
- 5
- 10
5. An internal combustion engine and its waterjacket, in combination with a water-supply tank for the jacket, a pump, a valve, and communicating connections between the tank, jacket, pump, and valve, the valve being adapted to normally establish communication between the jacket and the discharge side of the pump and to abnormally establish communication between the jacket
- 15
- 20
- and the suction side of the pump, the pump

being operable both to supply the jacket from the supply-tank and to drain the jacket of its water.

6. An internal combustion engine and its water-jacket, in combination with a water-supply tank for the jacket, a pump, a valve, and communicating connections between the tank, jacket, pump and valve, the valve being adapted to normally establish communication between the jacket and the discharge side of the pump and to abnormally establish communication between the pump and drain and between the jacket and the suction side of the pump, the pump being operable both to supply the jacket from the supply-tank and to drain both the jacket and the supply tank of their water.

In testimony whereof, I have signed my name to this specification.

AARON M. PAREIRA.
